(57) **CLAIM**

We claim the ornamental design for a display screen with an animated graphical interface, as shown and described.

DESCRIPTION

FIG. 1 is a front view of the first image in a sequence for a display screen with an animated graphical interface; FIG. 2 is a front view of the second image thereof; FIG. 3 is a front view of the third image thereof; FIG. 4 is a front view of the fourth image thereof; FIG. 5 is a front view of the fifth image thereof; FIG. 6 is a front view of the sixth image thereof; FIG. 7 is a front view of the seventh image thereof; FIG. 8 is a front view of the eighth image thereof; FIG. 9 is a front view of the ninth image thereof; FIG. 10 is a front view of the tenth image thereof; FIG. 11 is a front view of the eleventh image thereof; FIG. 12 is a front view of the twelfth image thereof; and, FIG. 13 is a front view of the thirteenth image thereof.

The appearance of the transitional image sequentially transitions between the images shown in FIGS. 1 through 13. The process or period in which one image transitions to another image forms no part of the claimed design.

The outermost broken-line rectangle illustrates the perimeter of the display screen and forms no part of the claimed design. The remaining broken lines illustrate portions of a graphical user interface and form no part of the claimed design.

(Continued)

Areas of the design shown with a stipple fill illustrate a contrast in visual appearance.
